TREATMENT OF MINERAL OILS BY HEAT

Walter James Perelis, Boston, Mass., assignor, by
mesne assignments, to Universal Oil Products
Company, Chicago, Ill., a corporation of South
Dakota

Application September 23, 1926, Serial No. 137,344
Renewed January 4, 1934

5 Claims. (Cl. 196—58)

This invention relates to improvements on processes dealing with cracking of mineral oils by heat.

5 I have experienced that agitation in one of its forms is essential when heating up hydrocarbon materials. In this way higher temperatures can be reached, without the danger of coking. The reason for this fact is the bad heat conductance of the oil, which does not allow a uniform heating up through the cross section, without agitation.

Such agitation can be produced either with the help of mechanical agitation or more simply and just as effectively with the help of turbulence in a tubular heater.

In the heating up period there is usually no gasoline present, therefore I put somewhat heavier hydrocarbons into the vapor phase to create the turbulence. Therefore comparatively lower pressures have to be used in the heating up period, if turbulence has to be created in a tubular heater. Pressures of the order of 200 pounds per square inch are suitable for such heating up.

25 After the material has been heated up to an effective cracking temperature, time on cracking temperature has to be given to it if big conversions are expected.

In this period pressures around 200 pounds per square inch are not high enough for maximum results. I have found it therefore advantageous to heat up the material under pressures of the order of 200 pounds per square inch and to increase the pressure of the flow after such heating up period. Such pressure increase is done with the help of a pump.

35 While I am agitating the material I heat it under pressure under flow to a maximum temperature.

40 If it should be attempted to pass into a tank shaped container oil on maximum cracking temperature to give the material time on cracking temperature during its passage through said container, a large amount of coke would be produced; but if the material is passed through a tubular apparatus in which it is turbulently flowing or if it is effectively agitated in a tank shaped container the coke formation will be practically eliminated.

45 To illustrate the above mentioned statement I am describing the result of my experiments. I have used Luling crude oil in two cases.

In one instance I have heated the oil under flow under pressure in a tubular heater to 860° F., then passed it through a heat insulated

chamber 6'x40'. In twenty hours I have filled up the tank with coke.

In the other case after heating up the material in the tubular heater to 890° F., it entered a tubular apparatus and was kept there under flow at a temperature around 890° F. while agitated with the help of turbulence; no appreciable amount of coke accumulated after two weeks of continuous operation.

55 For several years I have compared the quantities of coke produced per barrel of gasoline, in large scale refinery operation, in apparatuses using tanks, to give time for the material on cracking temperatures, with the quantities of coke produced in apparatus using tubular equipment or tanks equipped with efficient mechanical agitator and I find that I produced for oils like Luling crude oil 15 pounds coke per barrel of gasoline in tank shaped apparatus without mechanical agitator against one pound of coke in apparatuses where the material has been thoroughly agitated during the time on cracking temperatures. (In tubular apparatus the agitation is done with the help of turbulence.)

60 I have to remark that the rapid coke formation can be eliminated when using tanks without agitation if the entering temperature is kept low enough, which means conversion reduction.

65 To avoid such a loss the material should be heated up under pressure under flow through a tubular heater to a maximum temperature but after that before entering the tank without agitation it should pass first through an apparatus (insulated, tubular or tank with an agitator) and kept there in violent motion on cracking temperature until it loses some of its heat, while forming gasoline, until it reaches such a comparatively low temperature, which, though suitable for cracking conversions, does not result in coke formation when the material passes in the next step through a tank shaped apparatus which is not equipped with an agitator.

70 There are other means to reduce the coke production in apparatus using a tank shaped vessel to give time for the material on cracking temperature.

75 The material can be heated up under flow under high pressures to an effective cracking temperature, then the pressure can be partially reduced before entering the tank. In such a case the pressure reduction will cause a temperature reduction which is effective to reduce the coke formation; of course the temperature will be high enough yet for cracking conversions.

80 Another way to eliminate the coke accumula-

tion in the tanks is, in processes in which the material is heated to maximum temperature under flow and under pressure, to reduce the temperatures within the cracking range of the flow after the heating up period and before entering the tank. This can be accomplished economically in a heat exchanger in which the excess heat is given up to the feed material.

A combination, which worked out successfully is to heat up the material to a cracking temperature under pressures around 200 pounds under flow in a tubular heater, increase the pressure, continuing the flow through tubular heaters, decrease first the temperature for a period, then increase the temperature, reduce the temperature within the cracking range in a tubular apparatus, pass the material into a tank shaped apparatus, carry the material through the same while on effective cracking temperature, reduce the temperature to around 700° F. and relieve the pressure, allowing vaporization.

The described means are effective to produce with the help of heat a maximum amount of gasoline from heavier oils in different types of apparatus, eliminating at the same time the production of the huge amount of coke, which burdens the refiner using well introduced cracking processes today; upsetting at the same time the theory that the coke formation in cracking processes is a natural consequence of the gasoline production, because my process produces increased amount of gasoline, nevertheless eliminates practically the coke formation. It leads me to believe that the major part of the coke produced by well known cracking processes is not the consequence of the cracking proper, but the result of vaporization, which is not controlled.

The preferred form of apparatus is illustrated in diagram in Fig. 1 of the accompanying drawings.

Fig. 2 is a diagram with curves showing the approximate temperatures and approximate pressure conditions when treating crude oils in the preferred form of apparatus.

Fig. 3 is a diagram of a modified form of apparatus having drums provided with mechanical agitators.

The raw material is forced by pump 21 through a gasoline vapor heat exchanger 20, through line 38 to the top of vapor heat exchanger 16. In the said heat exchanger it meets the vapors released in vaporizer 14 coming through line 15. The result of this contact will be a separation of the light fractions of the raw material together with the light fractions of the cracked efflux, in vapor form, from a liquid consisting of the heavy fractions of the raw material together with the heavy fractions of the vapors of the cooled cracked efflux.

The liquid runs through pipe 39 into container 33 from where it leaves through line 1 and is pulled by the pump 2, which discharges it through heat exchanger 4, line 5 and heater 61, in which the material is heated up to an efficient cracking temperature while under pressures of the order of 200 pounds per square inch. With the help of pump 43 the pressure is increased and the material is moved through coil 71, in which the temperature is decreasing within the cracking range, then it moves through heater 81 where the temperature is increased, then it continues to flow through line 8, through tubular apparatus 10, through tank shaped container 11, through line 12, heat exchanger 4 and pressure

release valve 40 before it travels through line 13 to the vaporizer 14. Here the material is agitated with steam admitted through pipe 41 and spray pipe 42. A liquid which is fuel oil will separate out from vapors which enter the vapor heat exchanger 16 through line 15.

As before mentioned the temperature of the material decreases in 71; it increases again in 81 to the maximum. After this, instead of cooling down suddenly the material which is at effective cracking temperature, it is protected against outside heat losses. The material will then continue to produce gasoline for a substantial time while its temperature is decreasing. (A part of the sensible heat is consumed for the chemical reaction.)

The material leaving heater 81 passes first through a tubular apparatus 10 and then through a tank shaped container 11. If apparatus 10 should be left out, too much coke would accumulate in 11, but if the material is cooled in 10, while producing gasoline, to the order of 830° F. the coke formation will be eliminated later in 11. Preferably a valve 45 is provided in the line between the tubular member 10 and tank 11 to permit pressure reduction before entering the tank as hereinbefore mentioned.

The vapors of the cooled cracked efflux contact in 16 with the raw material. The result of this contact is a vaporous and a liquid fraction. The liquid fraction is accumulating in 33 and is handled as previously described. The vaporous fractions leave through 17 and enter the rectifier 18. Rectifier 18 is sprayed from the top 110 with gasoline passing through the valve 22 and is heated on the bottom, using the reboiler arrangement 30, 29, 28; a part of the material accumulating at the bottom of 18 is taken by the pump 30 and is discharged through the reboiler 29, where it is heated, back through 28 to the bottom of the tower.

The tower 18 will separate a vaporous fraction (gasoline) from a liquid (kerosene and light gasoil). The gasoline passes through line 120, heat exchanger 20, valve 23, line 24, water cooler 25, line 26 to a storage tank 27.

The kerosene and light gasoil pass through valve 31 or through valve 32. If they go through valve 31, then they pass through water cooler 125 34 and are accumulated in the storage tank 35. If I keep valve 31 closed, but open valve 32 the kerosene and light gasoil fractions can be mixed with the heavier oils in 33 and re-cracked.

The produced sediment free fuel oil leaves 130 the vaporizer 14, is cooled in water cooler 36 and is accumulated in tank 37. Coils 61, 81, 29 are built in a furnace as shown respectively at 6, 9 and 44. The parts 4, 71, 10, 11, 14, 16, 33, 18, 20 are heat insulated.

When the process is practiced as hereinbefore described by heating the material under flow and under high pressures to cracking temperature and then partially reducing the pressure by means of valve 45, a pressure reduction of 140 from 50 to 200 pounds is desirable before the flow enters the tank 11. Such a pressure reduction causes the temperature to be reduced sufficiently for the desired reduction of coke formation in the tank 11. The pressure is 145 further reduced after the oil stream leaves the tank 11 to support the vaporization in vaporizer 14. The vaporization is usually carried out at pressures close to atmospheric pressure in the vaporizer 14.

Referring to the modified form shown in Fig. 3, there are provided drums 61^a, 71^a, 81^a, 10^a, in place of the tubular coils 61, 71, 81 and 10, respectively, shown in Fig. 1, each of said drums 5 being provided with mechanical agitators. The drum 61^a is provided with rotary agitator shafts *a* and *a'* having agitator blades mounted thereon, the shaft *a* having a pulley 46 connected with any suitable driving mechanism, not shown, 10 said shaft *a* having driving connection with the shaft *a'*.

The drum 71^a is provided with rotary agitator shafts *a*², *a*³, each equipped with agitator blades, said shafts having driving connection with each other, the shafts *a*² having mounted thereon a pulley 46² connected with any suitable driving mechanism, not shown.

The drum 81^a is provided with rotary agitator shafts *a*⁴, *a*⁵, each equipped with agitator blades 20 and having driving connection with each other, the shaft *a*⁴ having a pulley 46² which may be driven by any suitable means, not shown.

The drum 10^a is equipped with rotary agitator shafts *a*⁶, *a*⁷, each provided with agitator blades 25 and having driving connection with each other, the shafts *a*⁶, *a*⁷ having a pulley 46³ driven by any suitable means, not shown.

The drums 61^a and 81^a are heated by the furnaces 6^a and 9^a respectively.

30 The pipe 5 leads from the heat exchanger 4 to the drum 61^a. The oil passes from the drum 61^a to the drum 71^a through pipe 61^b and the oil from drum 71^a passes to the drum 81^a through pipe 71^b. From drum 81^a it passes through pipe 8^a to drum 10^a and from drum 10^a it passes 35 through pipe 10^b to tank 11^a.

Located in pipe 10^b is a valve 45 whereby the pressure may be reduced before entering the tank 11^a as hereinbefore mentioned.

40 Preferably the drums 71^a, 10^a and 11^a are insulated against loss of heat.

The structure shown in Figure 3 as described is to replace the coils 61, 71, 81, 10 and the tank 11 in Figure 1 and is to be connected with 45 the heat exchanger 4 and the tank 14 and the other apparatuses associated with the apparatus containing the agitation means with the device illustrated and described in Figure 1.

What I claim is:

50 1. Process for cracking mineral oils by heat characterized by subjecting a liquid stream of oil while under turbulent flow in a tubular heater under pressure to a cracking temperature

and then to increase of temperature in succession, the temperature of the flowing stream remaining within the cracking range, while the pressure is decreasing, increasing and decreasing in succession.

2. Process for the treatment of mineral oils by heat comprising heating up the material under flow to a cracking temperature in the liquid-vapor phase under pressure, keeping the material in the cracking range for a substantial time, increasing the pressure after said heating up, reducing the temperature within the cracking range in a tubular apparatus under turbulent flow, further decreasing the temperature within the cracking range without turbulent flow, then reducing the temperature below the effective cracking range, then reducing the pressure to practically atmospheric pressure.

3. Process for the treatment of mineral oils by heat comprising heating up the material under flow to a cracking temperature in the liquid-vapor phase under pressure, keeping the material in the cracking range for a substantial time, increasing the pressure after said heating up, reducing the temperature within the cracking range while agitating, further reducing the temperature below the effective cracking range, then reducing the pressure.

4. Process for the treatment of mineral oils by heat comprising heating up the material under flow to a cracking temperature in the liquid-vapor phase under pressure, keeping the material in the cracking range for a substantial time, increasing the pressure after said heating up, reducing the temperature of the material within the cracking range while agitating, further decreasing the temperature within the cracking range without agitation, then reducing the temperature below the cracking range, then reducing the pressure.

5. Process for the treatment of mineral oils by heat comprising heating up the material under flow to a cracking temperature in the liquid-vapor phase under pressure, keeping the material in the cracking range for a substantial time, increasing the pressure after said heating up, reducing the temperature within the cracking range in a tubular zone under turbulent flow, further reducing the temperature below the cracking range, then reducing the pressure to practically atmospheric pressure.
